ABRASIVE IMPLEMENT

Randall S. Manchester, Troy, N. Y., assignor to
Behr-Manning Corporation, Troy, N. Y., a corporation of Massachusetts

Application August 14, 1942, Serial No. 454,843

12 Claims. (Cl. 51—185)

The present invention relates to a new and improved abrasive article or implement. More particularly, the invention provides a new construction in an abrasive "bob."

Implements of this class are used in industry for grinding, abrading, and smoothing relatively inaccessible portions of products being manufactured, such as in the operation of trimming and smoothing metal castings and the like. Abrasive bobs are employed in grinding metal castings in places that are inaccessible to larger grinding or cutting tools.

As is well understood in the art, these bobs are mounted on the end of a rotatable spindle connected to a source of power by a flexible shaft, or, in some cases, they are mounted directly on an electric drill. The relatively small rapidly rotating bob may be readily inserted into places where it would be impossible to use a grinding wheel or other finishing device.

Prior to the present invention, abrasive bobs were of two standard types. The first was a vitrified or similarly bonded abrasive grain bob, molded about a metal shank or spindle and baked or hardened in the desired form. Bobs of this type were unsatisfactory because of their rigid nature, their tendency to "load" due to the fact that the grain is embedded in the bond, and their tendency to chatter when used, due to their solid character. The other type of bob was made up from a felt or other soft body, formed to the desired shape and dipped in glue and abrasive grain, alternately a plurality of times, until a thick layer of glue and sand encased the soft body. Bobs of this type were better than the vitrified type, except that their production required considerable labor and expense. Moreover, since it is impossible to control the quantity of glue and grain, neither type provided an abrading implement which was as efficient as coated abrasive material, such as sandpaper or abrasive cloth.

An object of the invention is to overcome the inherent defects of abrasive bobs of the prior art and to produce an improved implement at less cost.

A further object of the invention is to provide an abrasive bob having the efficient abrasive characteristics of coated abrasives, yet having a shape similar to or identical with the shapes of molded or dipped bobs of the prior art.

A further object of the invention is to provide an abrasive bob which is relatively soft and flexible and which can be deformed somewhat in use, to conform to the surface to be abraded.

A further object of the invention is to produce an abrasive bob which is long wearing in use and which has a markedly decreased tendency to become loaded or clogged with the abraded material.

A further object of the invention is to provide an abrasive bob which will present substantially fresh abrasive surfaces, repeatedly, as the original surfaces are worn away in use.

Other and further objects and advantages of the invention will be apparent to those skilled in the art from a consideration of the following description of a specific embodiment of the invention, shown in the accompanying drawings, in which:

Figure 1 is a vertical sectional view of a bob in accordance with the present invention.

Figure 2 is a side elevation thereof.

Figure 3 is a vertical sectional view showing a different shape.

Figure 4 is a plan view of a blank from which the bob is made.

Figure 5 is a bottom plan view of Figure 3, and

Figures 6-11 illustrate other shapes of bobs and the blank from which they may be made.

In constructing a bob in accordance with the present invention, a strip of sandpaper or abrasive cloth 15 is cut to the desired shape, with one end 16 equal in width to the height of the desired bob, such as one and one-half inches, and of a length sufficient to form the desired maximum diameter of the bob when the strip is wound into a roll, taking into consideration the thickness of the sheet and the size of the bore in the interior of the bob. The back, non-sanded surface of the blank may be coated with adhesive, as indicated at 17, in a strip along one edge of the blank. The blank is then wound upon a mandrel to form a roll consisting of a plurality of convolutions secured together by the adhesive 17.

As shown in Figure 4, one edge 18 of the blank is at right angles to the edge 16 which is first wound upon the mandrel. Hence, the various convolutions of the edge 18 in the finished product will all lie in a common plane 18', normal to the axis of the winding mandrel. The other edge 19, however, is tapered and approaches the edge 18, from the wide to the narrow end of the blank. Hence, the edge 19 in the finished product recedes from the end 20 of the bob toward the butt end 18'. In other words, each convolution of the edge 19 is stepped back from the one therebelow, to expose a portion of the abrasive surface thereof. This gradual receding of the edge

of the strip in successive convolutions imparts to the bob as a whole, the desired tapered, conical, convexly rounded shape, as indicated in Figures 1, 2, 3, 6, and 8.

Practically any desired shape of bob can be produced, by appropriately designing the blank before it is wound on the mandrel. If a relatively blunt bob is desired, the angle between edges 19 and 18 should be decreased, as indicated in Figure 9, whereas if a more pointed, sharply tapered bob is to be produced, the angle should be increased, as indicated in Figure 4. Figures 6 and 7 illustrate an intermediate shape.

As stated above, the adhesive 17 may be applied in the form of a strip along the base edge of the blank so that the convolutions are secured together only adjacent the butt end of the finished product, leaving the forward, working end relatively soft and flexible. If desired, however, the blank may be coated with adhesive over its entire area, thereby securing all portions of the convolutions together and producing a more rigid grinding implement. The extent of coverage of the blank with adhesive can be varied within wide limits, to secure a corresponding variation in the flexibility and rigidity of the finished product.

After the bob has been produced, it may be used on a spindle 25 having a smooth reduced end 26, an intermediate threaded section 27 and an abutment shoulder 28. The threads 27 may readily be screwed into the paper or cloth constituting the wall of the hollow bore 29 of the implements, to secure the same upon the spindle. The threads 27 project outwardly slightly beyond the diameter of the smooth end 26, the latter being of the same size as the winding mandrel and the bore of the implement. Any similar spindle or rotatable support may be used, such as one provided with flutes, a taper, or the like.

As shown in Figures 10 and 11, a bob in accordance with the present invention may be produced from a strip 30 having parallel side edges. In this case, the strip is wound on the mandrel so that successive convolutions are moved axially, progressively as the roll is built up. As a result, one end 31 of the implement is convexly rounded and the other 32 has a similar concavity formed therein. A bob of this type may be mounted upon a spindle 33 provided with a rigid supporting head or plug 34 adapted to support the hollow base end of the bob and to which the latter may be secured by adhesive, if desired. On the other hand, the rear end may be left unsupported, if a flexible skirt at that end is desired.

As indicated in Figure 1, the strip of coated abrasive material is wound up with the abrasive surface facing outwardly in all of the convolutions and with the backing facing inwardly. The backing preferably is cloth, although any other materials, such as paper and the like, may be employed.

The exposed surfaces of the coated abrasive, although actually disposed on substantially concentric cylindrical or spiral surfaces, present a tapering, conical, or convexly rounded abrasive surface to the implement as a whole because of their progressively stepped relation, each to the other. Hence, in use, the article functions in the same manner as a molded or dipped abrasive bob.

Moreover, as successive layers of the coated abrasive are worn away, completely fresh layers are exposed for subsequent use. These fresh sur-

faces function with the same efficiency as the original surfaces. In this connection, it is important to note that, at the working end of the implement, the spaces between the grains in successive layers are not filled with adhesive, as is the case at the base end. Hence, the cutting efficiency of the layers is not impaired by the presence of adhesive employed to secure the convolutions to each other.

It is thought that, from the foregoing description, the nature and advantages of the present invention will be entirely clear to those skilled in the art. It must be understood that the invention is not limited to the details of construction, described above and shown in the accompanying drawing, but covers all modifications coming within the scope of the appended claims and their equivalents.

I claim:

1. An abrasive implement having a base and a tapered forward working end, comprising a coated abrasive strip wound upon itself in a plurality of contacting convolutions with the abrasive surface disposed outwardly, the edge of the strip in successive convolutions adjacent the forward end being stepped back from the corresponding edge of the convolutions therebelow and exposing the abrasive surface thereof and thereby imparting a convex tapered shape to the forward working end of the implement as a whole, the successive convolutions adjacent said forward working end being unsecured to each other, thereby providing a substantially yielding and resilient working end.

2. An abrasive implement having a base and a tapered forward working end, comprising a plurality of mutually contacting convolutions of coated abrasive wound with the abrasive surface outwardly and with an edge of successive convolutions adjacent the forward end positioned to expose the abrasive surface of the convolutions therebelow, thereby providing a generally tapered or conical abrasive surface at the forward working end of the implement, the contacting convolutions adjacent the forward end being unsecured to each other, thereby providing a yielding and resilient abrasive surface.

3. An abrasive implement comprising a plurality of contacting convolutions of coated abrasive adhesively secured together adjacent the base end of the implement only and wound with an edge of successive convolutions positioned remote from the base end to expose a marginal portion of the abrasive surface of the convolutions therebelow, thereby providing a yielding, resilient, generally convex abrasive surface at the working end of the implement.

4. An abrasive implement having a base and a working face at the opposite end, comprising a coated abrasive strip wound upon itself in a plurality of contacting convolutions with the abrasive surface disposed outwardly, the axially outermost edge of the convolutions being progressively stepped back toward the base end to provide a convexly rounded working end face for the implement as a whole, the successive convolutions adjacent the working end being unsecured to each other, thereby providing a relatively yielding and resilient working end face.

5. An abrasive implement having a base end and a working face at the opposite end comprising a coated abrasive strip wound upon itself in a plurality of contacting convolutions with the abrasive surface disposed outwardly, the axially

outermost edge of successively wound convolutions being progressively stepped back to provide a tapered abrasive working end for the implement as a whole, the successive convolutions being adhesively secured to each other adjacent the base end only, leaving the convolutions in the working end unsecured, thereby providing a relatively rigid base and a relatively yielding and resilient working end.

6. An abrasive bob having a base and a working end, comprising a tapered, coated abrasive strip wound upon itself in a plurality of contacting convolutions adhesively secured together with one edge of successive convolutions lying in a single transaxial plane at the base of the bob and the other edge stepped back progressively and exposing the abrasive surface of the successively wound convolutions and providing a generally convex, tapered working end for the bob as a whole, the spaces between the grains in successive layers adjacent the working end of the bob being relatively free from adhesive such as would impair the abrasive efficiency of said working end.

7. An abrasive bob having a base at one end and a working face at the other, comprising a tapered, coated abrasive strip wound upon itself in a plurality of contacting convolutions with one edge of successive convolutions lying in a single transaxial plane at the base of the bob, and a layer of adhesive adjacent said one edge only of the strip securing the successive convolutions together, the other edge of the strip being stepped back progressively from the innermost to the outermost convolution, and exposing the abrasive surface of each inner convolution axially therebeyond, and providing a generally tapered abrasive working end face for the bob as a whole.

8. A bob in accordance with claim 6 characterized in that the convolutions adjacent the first mentioned edge of the strip are adhesively united to each other and in that the convolutions at the opposite end of the bob are in contact with each other but are unsecured, thereby providing a flexible working end face.

9. An abrasive implement having a base end and a working end comprising a strip of coated abrasive cloth wound spirally in a plurality of contacting convolutions with one edge progressively and spirally receding from the working end of the roll toward the base end in successively wound convolutions and providing a generally tapered abrasive working surface, the successive convo-

lutions of abrasive cloth adjacent the working end being unsecured to each other, thereby providing a relatively yielding and resilient abrasive surface.

10. An abrasive implement comprising a strip of coated abrasive cloth of substantially constantly increasing width from one end to the other, tightly wound spirally into a roll having successive convolutions in contact and with the wider end innermost and the narrower end outermost, and with the grain in successive convolutions facing outwardly, thereby imparting a convex shape to the working end face of the implement, the successive convolutions of abrasive cloth adjacent the working end face of the implement being unsecured to each other, thereby providing a substantially yielding and resilient end face.

11. An abrasive implement having a base end and a working end comprising a longitudinally tapered strip of coated abrasive cloth tightly wound in a roll having successive convolutions in contact and with the abrasive surface facing outwardly and with the wide end of the strip adjacent the center of the roll, the edge of the strip in successive convolutions at the base end of the implement being disposed in a single plane and being adhesively secured together, and the other edge receding in successively wound convolutions from the opposite end of the implement to provide a tapered abrasive working surface, the successive convolutions of abrasive cloth adjacent the last mentioned edge being unsecured to each other, thereby providing a relatively yielding and resilient working surface.

12. An abrasive implement having a base and a tapered forward working end, comprising a coated abrasive strip wound upon itself about a longitudinal axis in a plurality of spiral, contacting convolutions with the abrasive surface disposed outwardly, said tapered forward working end having a surface such that all axial planes through the implement intersect the surface on parallel lines spaced progressively outwardly from the axis a distance substantially equal to the thickness of the coated abrasive strip, the contacting convolutions being adhesively secured to each other adjacent the base end only, leaving the convolutions unsecured at the forward end, to provide a relatively yielding and resilient abrasive surface.
